United States Patent Office

Des. 178,189
Patented July 3, 1956

178,189

SCROLL CHRISTMAS TREE OR SIMILAR ARTICLE

Curtis Gunter, New York, N. Y., assignor to Austen Display Inc., New York, N. Y., a corporation of New York

Application December 19, 1955, Serial No. 39,389

Term of patent 3½ years

(Cl. D29—1)

Fig. 1 is a plan view of a scroll Christmas tree or similar article, showing my new design; and

Fig. 2 is a sectional view thereof taken on line 2—2 of Fig. 1.

I claim:

The ornamental design for a scroll Christmas tree or similar article, as shown.
